CLAIM

The ornamental design for a mechanical claw, as shown and described.

DESCRIPTION

FIG. 1 is a top, front perspective view of a mechanical claw, showing my new design in an open state;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a top, front perspective view showing the mechanical claw in a closed state;
FIG. 10 is an enlarged detail view of area 10 in FIG. 1; and,
FIG. 11 is an enlarged detail view of area 11 in FIG. 2.
The broken lines in the drawings illustrate the portions of the mechanical claw, which form no part of the claimed design.
The dash-dot-dash broken lines encircling the enlarged views are for annotative purposes only and form no part of the claim thereof.
